UNITED STATES PATENT OFFICE.

SIMON C. COLLIN, OF WISSAHICKON, PENNSYLVANIA, ASSIGNOR OF ONE-HALF TO WILLIAM WHITE, JR., OF PITTSBURG, PENNSYLVANIA.

CHARGING AND DRAWING APPARATUS.

SPECIFICATION forming part of Letters Patent No. 686,508, dated November 12, 1901.

Application filed August 17, 1901. Serial No. 72,363. (No model.)

To all whom it may concern:

Be it known that I, SIMON C. COLLIN, a citizen of the United States, residing at Wissahickon, city of Philadelphia, in the county 5 of Philadelphia and State of Pennsylvania, have invented certain new and useful Improvements in Charging and Drawing Apparatus; and I do declare the following to be a full, clear, and exact description of the invention, 10 such as will enable others skilled in the art to which it appertains to make and use the same, reference being had to the accompanying drawings, and to the letters of reference marked thereon, which form a part of this 15 specification.

In my Letters Patent No. 565,434, issued August 11, 1896, is shown, described, and claimed an apparatus for charging and drawing metal to and from heating-furnaces, 20 which apparatus is comprised of a table composed of a series of rollers which receive and feed the billets or other metal bodies and a ram supported on the feeding-rollers and adapted to engage and feed the billet and to 25 withdraw it from the furnace.

My present invention is directed to improvements on the apparatus which forms the subject-matter of my said Letters Patent, the improvements, broadly considered, 30 consisting of a movable carrier, a conveyer on the carrier, and a ram movably supported on the carrier independent of and adjacent to the conveyer.

One advantage possessed by my improvements resides in the increased facility for 35 moving the metal over the table. The rollers in the present construction do not afford the support for the ram, and the path of the metal being unobstructed the metal may be 40 rapidly conveyed from one end of the table to the other, the ram serving, through a gripping device, such as the usual tongs, to deliver the metal on the rollers and to finish the charge to the furnace by a ramming action 45 when moved by the carrier in line with the metal and furnace-opening.

The nature of my improvements will be understood, reference being had to the following detailed description and to the accompanying drawings, in which—

Figure 1 is a plan view of a charging and drawing apparatus embodying my invention. Fig. 2 is a front elevation. Fig. 3 is an end view. Fig. 4 is a longitudinal sectional view on line 4-4 of Fig. 1. Fig. 5 is a transverse 55 sectional view on line 5-5 of Fig. 1.

Referring to the drawings by letter, A denotes the carrier, consisting of an angle-iron frame mounted to be moved transversely by flanged wheels b b on tracks c c. Mounted 60 longitudinally on the movable carrier, toward one side thereof, is a series of feeding-rollers D D, to the shafts d d of which are secured beveled gear-wheels d' d'', which engage beveled gear-wheels e e, commonly fixed to a shaft e'. 65 Any suitable power means may be provided to drive the rollers D. I preferably employ, however, an electric motor F, the drive-shaft of which is geared to the shaft e'. Similarly there is employed to move the carrier an 70 electric motor G, the driving-shaft of which is geared to an intermediate shaft h, and the latter is connected by gearing to the axles of the traction-wheels b, of which there are preferably two sets, as shown.

I designates the ram, slidably mounted by flanged wheels j j on rails a a, arranged longitudinally of the carrier adjacent to the series of feeding-rollers and preferably forming a part of the carrier-frame. On the under side of the ram and parallel with the sides thereof is a rack-bar i, which is engaged by a pinion k, fixed to a shaft k', journaled transversely on the carrier. The shaft is connected by suitable gearing with the 85 driving-shaft of an electric motor L or other source of power, and m is a friction-clutch interposed between the shaft k' and the gear connection with the motor, whereby the rotation of the shaft k' and pinion k and the 90 consequent movements of the ram may be controlled by an operator.

The movable ram carries a platform n, which in practice is occupied by an operator, and on the ram are a number of pins o o, to 95 which is connected the chain of the metal-grasping tongs. (Not shown.) The tongs are preferably manipulated by the operator occupying the platform to grasp the billet, bloom, ingot, or other metal body, and by 100

means of a controller G' the motor G is operated to move the carrier to bring the feeding-rollers in line with the metal. The tongs-chain being connected with the ram, both the 5 latter and the feeding-rollers are set in motion through the manipulations of controllers L' and F', electrically connected, respectively, with the motors L and F, with the result of drawing the metal on the rotating rollers and 10 feeding it by the latter partly into the heating-furnace opening. The charge is finished by the ram, which after the metal has left the rollers is brought by the movement of the carrier into line with the metal, whereupon 15 the ram is set in motion, and the nose i' thereof engaging the end of the metal the latter is forced into the furnace the desired extent.

It will be observed that the ram is movably supported independently of the feeding-rollers, and hence the ram at no time impedes 20 the movement of the metal while being conveyed by the rollers. The path of the metal being unobstructed, it may be conveyed very speedily by the rollers over the table, and 25 thus may be effected a material saving in time, labor, and expense incident to the operation.

After the metal has become heated in the furnace it is grasped by the tongs and drawn by the reverse movement of the ram on the 30 rollers, the direction of rotation of which is reversed, and conveyed by the latter to the shaping-machine, the carrier being moved previously to the delivery of the metal on the rollers to bring the latter into proper alignment. 35

I claim as my invention—

1. In an apparatus for charging and drawing metal to and from heating-furnaces, the combination of a movable carrier, feeding- 40 rollers on said carrier, and a movable ram mounted on the carrier out of the path of the

metal but arranged to be brought into the path of the metal by movement of the carrier.

2. In an apparatus for charging and drawing metal to and from heating-furnaces, the 45 combination of a movable carrier, feeding-rollers on the carrier, tracks on the carrier at one side of the feeding-rollers, and a movable ram supported by wheels on said tracks.

3. In an apparatus for charging and drawing metal to and from heating-furnaces, the combination of a movable carrier, feeding-rollers on said carrier, a ram movably supported on the carrier independently of the feeding-rollers and a platform carried by the 55 ram.

4. In an apparatus for charging and drawing metal to and from heating-furnaces, the combination of a movable carrier, feeding-rollers on said carrier, a ram movably supported on the carrier independently of the rollers and movable into the path of the metal by movement of the carrier, and reversible power means including a clutch for moving the ram. 60

5. In an apparatus for charging and drawing metal to and from heating-furnaces, the combination of a movable carrier, a conveyer on the carrier, a ram movably mounted on the carrier and carrying pins, a rack-bar and 70 a nose, a pinion engaging the rack-bar, reversible power means including a friction-clutch for actuating the pinion, and power means for operating the conveyer and for moving the carrier. 75

In testimony whereof I affix my signature in presence of two witnesses.

SIMON C. COLLIN.
